UNITED STATES PATENT OFFICE.

LEVARTT ARMISON, OF BUFFALO, NEW YORK.

MECHANICAL POKER FOR GAS-FURNACES.

SPECIFICATION forming part of Letters Patent No. 593,546, dated November 9, 1897.

Application filed June 27, 1895. Renewed March 16, 1897. Serial No. 627,893. (No model.)

To all whom it may concern:

Be it known that I, LEVARTT ARMISON, a citizen of the United States, residing at Buffalo, in the county of Erie and State of New York, have invented a new and useful Improvement in Mechanical Pokers for Gas-Furnaces, of which the following is a specification.

This invention relates to mechanism which is more particularly designed for operating a poking implement in a gas-furnace for breaking up the bridges or arches which are liable to be formed in such furnaces, and also for compacting the fuel to prevent air from passing too freely through the same.

My invention has for its object to provide an effective mechanical poker of this character which is operated automatically and in a reliable manner.

In the accompanying drawings, consisting of four sheets, Figure 1 is a sectional elevation of a cupola or gas furnace provided with my improvement. Fig. 2 is an enlarged top plan view of the operating mechanism with a portion thereof broken away to expose subjacent parts. Fig. 3 is an enlarged horizontal section of the clutch and reversing mechanism of one of the drum-shafts. Fig. 4 is a top plan view of the guide which coöperates with the reversible follower of the clutch. Fig. 5 is a transverse vertical section, on an enlarged scale, in line 5 5, Fig. 2. Fig. 6 is a sectional elevation of one of the clutch-wheels and its driving-gear. Fig. 7 is a transverse section in line 7 7, Fig. 3.

Like letters of reference refer to like parts in the several figures.

A is a cupola or gas furnace of any ordinary construction.

B represents one or more pokers arranged within the fireplace of the furnace and adapted to be dropped at intervals upon the bed of fuel in the furnace for agitating and compacting the same and breaking up any arch or bridge that may be formed by the fuel. These pokers consist of comparatively heavy weights having preferably the form of balls, as shown in Fig. 1. In the drawings a number of such poker-balls are shown, and as the operating devices of these several balls are alike a description of one will apply to all.

C represents a horizontal drum arranged at the top of the cupola and secured to a hori-

zontal shaft c, which is journaled in bearings formed in standards D and in the sides of a housing D', which incloses the drum. These 55 standards rise from a base-plate D², resting on the top of the cupola.

E is a chain or cable which is wound upon the drum C and from which the poker-ball is suspended.

f is a ratchet-wheel secured to the drum-shaft, and f' a detent-pawl pivoted to the base-plate or other stationary support and adapted to engage with said ratchet-wheel for holding the drum temporarily against backward rotation and preventing the descent of the ball. This pawl is held in engagement with the ratchet-wheel by a spring f².

g is a horizontal detent-releasing shaft arranged above the drum, as shown in Fig. 5, 70 and supported in bearings arranged on the housing D', and g' is a cam secured to said shaft and adapted to operate against the free upper portion of the detent-pawl f' once during every revolution of said shaft, so as to 75 disengage the pawl from the ratchet-wheel of the drum-shaft and release the drum, thereby allowing the weight to descend and unwind its supporting-chain from the drum.

g² is a toothed or star wheel which is secured to the releasing-shaft g and which is turned intermittently by a rotary arm or tappet h, having a projecting pin or roller h', which engages with the teeth of the star-wheel. This tappet is mounted on a counter-shaft h², supported on the housing D'. An intermittent rotary movement is imparted to the counter-shaft h² by a ratchet-wheel h³, secured thereto, and an actuating-pawl h⁴, engaging with said wheel and carried by an 90 oscillating arm h⁵, which is pivoted upon the counter-shaft. This oscillating arm is actuated from the main driving-shaft I by an eccentric i and connecting-rod i', having a strap which embraces the eccentric, as shown in Fig. 95 5. The main driving-shaft is arranged horizontally above the releasing-shaft g and is continuously driven from any available source, said shaft being provided with a driving-wheel I'.

By the mechanism just described the counter-shaft h² is turned forward the distance of one tooth of its ratchet-wheel during every rotation of the main shaft, and the pawl-re-

leasing shaft, through the medium of the star-wheel and the tappet of the shaft h^2 , is turned forward the distance of one tooth of the star-wheel during every complete turn of the counter-shaft. The cam of the releasing-shaft disengages the detent-pawl from the ratchet-wheel of the drum once during every rotation of said shaft, and as soon as said cam clears the detent the latter is again forced into engagement with the ratchet-wheel by its spring. As soon as the descending poker-ball strikes the bed of fuel the movement of the drum is automatically reversed for again winding the chain thereon and raising the poker-ball preparatory to its next descent. The mechanism whereby this reverse movement is effected is constructed as follows:

5 J is a continuously-rotating clutch or driving wheel which turns loosely on the drum-shaft and which is rotated in the direction in which the drum turns in winding up the chain by means of a sprocket-chain or belt J' , running around the clutch-wheel and a sprocket-wheel J^2 , secured to the main driving-shaft.

10 K represents radially-movable clutch-shoes connected with the drum-shaft and adapted to bear against the inner side of the rim of the clutch-wheel J , so as to compel the shaft to turn with the wheel. These shoes consist of two segmental or semicircular sections which are guided on radial arms k , secured to the drum-shaft by means of a hub or sleeve k' , as shown in Figs. 3 and 6. The clutch-shoes 15 are expanded and contracted by rotary right and left hand screws k^2 , which engage in correspondingly-screw-threaded sockets formed in the opposing ends of the shoes. Each of these screws has an arm k^3 for turning it.

20 l is a reciprocating collar arranged to slide on the sleeve k' , and l' represents links which connect the outer ends of the screw-operating arms k^3 with said collar, so that by the forward movement of the collar the arms are caused to turn the screws in the proper direction to move the shoes outward into contact with the clutch-wheel, while by the backward movement of the collar the screws are turned in the opposite direction and the shoes are 25 withdrawn from the clutch-wheel.

25 M is a screw-nut or follower which is actuated by the rotation of the drum-shaft and which is adapted to shift the clutch-collar l forward for applying the clutch-shoes and reversing the movement of the drum. This screw-nut or follower engages with an externally-screw-threaded portion m of the drum-shaft and is held against turning thereon by an arm m' , extending downwardly from the 30 follower and sliding in a longitudinal guide or way m^2 , supported on an arm m^3 of the base-plate. This guide compels the follower to traverse the screw-threaded portion of the drum-shaft in one or the other direction, according to the direction in which the latter turns. The trend of the screw-thread of the shaft is such that the follower is moved to-

ward the clutch-collar by the backward or unwinding movement of the drum and away from said collar by the forward or winding movement of the same.

35 n is a cushioning-spring which bears against the rear end of the clutch-collar, and n' a washer which in turn bears against the rear end of said spring. The follower upon 75 being advanced by the backward rotation of the drum-shaft comes in contact with the washer n' and through the medium of the spring n shifts the clutch-collar forward, whereby the clutch-shoes are applied to the 80 clutch-wheel and the drum-shaft is thrown into gear with the latter, thus reversing its movement.

40 o o^2 represent a horizontal shifting frame or yoke connected with the clutch-collar and 85 adapted to shift the collar backward at the moment the poker-ball has been sufficiently elevated by the reverse motion of the drum, so as to again throw the drum-shaft out of gear with the clutch-wheel and allow it to remain at rest until it is again released by its 90 detent-pawl. This shifting frame consists of front and rear cross-heads o o' , which are arranged to slide upon the portions of the drum-shaft immediately in front and in rear of its 95 external screw-thread and which are connected by tie-rods o^2 . These rods preferably pass loosely through openings formed in the follower M , as shown in Fig. 3. The front cross-head o is formed centrally with an annular opening which receives the clutch-collar and is confined between shoulders o^3 , formed on the latter, so as to compel the 100 clutch-collar to move rearward with the shifting frame, while allowing the collar to turn 105 in its front cross-head.

45 p represents adjustable stops, which project forwardly from the rear cross-head of the shifting frame and against which the follower M is adapted to bear when it is moved rearward by the forward rotation of the drum-shaft, thereby sliding the shifting frame in the same direction and causing it to move the clutch-collar in the proper direction to release the clutch-shoes. A cushioning-spring q is 110 preferably arranged on the front side of the rear cross-head of the shifting frame for receiving the impact of the follower. The cushioning-springs n and q also serve to suddenly accelerate the shifting movement of the 115 clutch-collar as soon as the links l' pass the dead-center, thus effecting the movements of the clutch-shoes quickly and reversing and stopping the drum promptly.

50 The operation of my improved mechanical poker is as follows: In the normal operation of the parts the poker-supporting chain is wound upon the drum. The latter is held against turning by its detent-pawl, and the drum-shaft is out of gear with the reversing 130 mechanism. As soon as the intermittently-rotating cam of the releasing-shaft disengages the detent-pawl from the ratchet-wheel of the drum-shaft the latter is turned backward by

the unwinding of the chain caused by the dropping of the poker-ball. The backward rotation of the drum in unwinding the chain causes the follower M of the clutch to be fed 5 toward the clutch-collar, and immediately after the poker-weight has struck the fuel the follower comes in contact with said collar and shifts it forward, thereby applying the clutch-shoes and causing the movement of the drum 10 to be reversed, whereby the chain is wound upon the drum and the poker-ball is elevated preparatory to being again dropped. This reverse motion of the drum-shaft causes the follower to be fed in the opposite direction 15 or toward the rear cross-head of the clutch-shifting frame, and at the moment that the chain is sufficiently wound upon the drum the follower comes in contact with the stops p of the shifting frame and moves the latter 20 outward, thereby shifting the clutch-collar in the same direction, disconnecting the drum-shaft from the clutch-wheel, and preventing its further rotation. When the detent-pawl of the drum is again disengaged, these operations 25 are repeated, the poker-ball being thus elevated and dropped alternately by the automatic action of the clutch and the reversing mechanism. The relative movements of the parts are so timed that the detent-pawl 30 is allowed to move into position for engaging with the ratchet-wheel of the drum by the time that the poker-ball is raised, so as to prevent retrograde movement of the drum and hold the ball in its elevated position. 35 When a number of poker-balls are employed, their operating-drums are mounted on separate shafts, and each shaft has an independent clutch and reversing mechanism, as shown in the drawings, but only one releasing mechanism is required for disengaging the detent-paws of the several drums. In the drawings 40 four poker-balls and drums are shown. Two of the drum-shafts are driven directly from the main shaft by sprocket wheels and chains, 45 while the other drum-shafts are likewise driven from a counter-shaft I², which is in turn driven from the main shaft by gear-wheels I³ I⁴, as shown in Figs. 2 and 5. The detent-paws of one pair of drums are released 50 by two cams mounted on the shaft g, while the detent-paws of the other two drums are released by similar cams mounted on a counter-shaft g³, which is driven from the main releasing-shaft g by gear-wheels g⁴ 55 g⁵. When such a series of poker-balls is employed, the releasing-cams are located at different quarters of their respective shafts, so that the several balls are dropped successively and at regular intervals, say, of about two 60 minutes.

My improved mechanism, though especially useful for the purpose herein described and shown, may also be employed in pile-drivers and other machines in which a weight is alternately elevated and dropped.

I claim as my invention—

1. In a mechanical poker, the combination

with a main driving-shaft, of a rotary drum, a chain or cable wound thereon and carrying a poker or weight, a detent for holding the drum against backward rotation, an automatic releasing device operating upon said detent and actuated from the main driving-shaft, and automatic reversing mechanism controlled by the rotation of the drum-shaft whereby the drum is turned forwardly for winding up the chain and raising said weight, substantially as set forth.

2. The combination with a rotary drum, a chain or cable wound thereon and a weight suspended from the chain, of a detent for holding the drum against backward rotation, a releasing device whereby said detent is disengaged from the drum, a driving-wheel rotating in the direction in which the drum turns in winding the chain thereon, a clutch whereby the drum-shaft is thrown into gear with said driving-wheel, and an automatic shifting device actuated from the rotating drum, whereby said clutch is operated, substantially as set forth.

3. The combination with a rotary drum having an externally-screw-threaded shaft, a chain or cable wound thereon and a weight suspended from the chain, of a detent for holding the drum against backward rotation, a releasing device whereby said detent is disengaged from the drum, a driving-wheel rotating in the direction in which the drum turns in winding the chain thereon, a clutch whereby the drum-shaft is thrown into gear with said driving-wheel, and a screw-nut or follower engaging with the screw-thread of the drum-shaft and operating said clutch, substantially as set forth.

4. The combination with a rotary drum having an externally-screw-threaded shaft, a chain or cable wound thereon and a weight suspended from the chain, of a detent for holding the drum against backward rotation, a releasing device whereby said detent is disengaged from the drum, a driving-wheel rotating in the direction in which the drum turns in winding the chain thereon, a clutch whereby the drum-shaft is thrown into gear with said driving-wheel, a shifting frame connected with the actuating-collar of said clutch, and a screw-nut or follower engaging with the screw-thread of the drum-shaft and adapted to operate alternately against said shifting frame and the actuating-collar of the clutch, substantially as set forth.

5. The combination with a rotary drum having an externally-screw-threaded shaft, a chain or cable wound thereon and a weight suspended from the chain, of a detent for holding the drum against backward rotation, a releasing device whereby said detent is disengaged from the drum, a driving-wheel rotating in the direction in which the drum turns in winding the chain thereon, a clutch whereby the drum-shaft is thrown into gear with said driving-wheel, a shifting frame connected with the actuating-collar of said clutch,

a screw-nut or follower engaging with the screw-thread of the drum-shaft and adapted to operate alternately against said shifting frame and the actuating-collar of the clutch, 5 and cushioning-springs interposed between said follower and the shifting frame and clutch-collar, substantially as set forth.

6. The combination with a rotary drum, a chain or cable wound thereon, and a weight 10 suspended from the chain, of a detent for holding the drum against backward rotation, an intermittently-rotating releasing-shaft having a cam adapted to operate against said detent, a driving-wheel rotating in the direction in which the drum turns in winding the chain thereon, a clutch whereby the drum-shaft is thrown into gear with said driving-wheel, and an automatic shifting device actuated from the drum and operating said clutch, substantially 15 as set forth.
7. The combination with a rotary drum, a 20

chain or cable wound thereon, and a weight suspended from the chain, of a detent for holding the drum against backward rotation, a releasing-shaft having a toothed actuating-wheel and a cam adapted to engage against said detent, a counter-shaft having a tappet engaging with the toothed wheel of the releasing-shaft, a ratchet device whereby said counter-shaft is intermittently rotated, a 25 driving-wheel rotating in the direction in which the drum turns in winding the chain thereon, a clutch for throwing the drum-shaft into gear with said driving-wheel, and an automatic shifting device actuated from the 30 drum and operating said clutch, substantially as set forth.

Witness my hand this 3d day of June, 1895.
LEVARTT ARMISON.
